UNITED STATES PATENT OFFICE.

WILLIAM V. ROBINSON, OF OWOSSO, MICHIGAN, ASSIGNOR TO INDEPENDENT STOVE COMPANY, OF OWOSSO, MICHIGAN, A CORPORATION OF MICHIGAN.

DESIGN FOR A COMBINED GAS STOVE AND COAL RANGE.

Application filed August 27, 1923. Serial No. 7,103. Term of patent 14 years.

To all whom it may concern:

Be it known that I, WILLIAM V. ROBINSON, a citizen of the United States of America, residing at Owosso, in the county of Shiawassee and State of Michigan, have invented a certain new, original and ornamental Design for a Combined Gas Stove and Coal Range, of which the following is a specification, reference being had therein to

the accompanying drawings, forming part thereof, in which the figure is a front perspective view of a combined gas stove and coal range, showing my new design.

I claim:

The ornamental design for a combined gas stove and coal range, as shown.

WILLIAM V. ROBINSON,
